Office Action dated Aug. 8, 2011 for Japanese Design Application No. D2011-003843 with Tanizawa Hard Hat T-06 product information.

Primary Examiner — Rosemary K Tarcza(74) *Attorney, Agent, or Firm* — Melanie G. Gover(57) **CLAIM**

The ornamental design for vent openings in head gear, as shown and described.

DESCRIPTION

FIG. 1 is a perspective view of a head gear showing the new design for vent openings in head gear;

FIG. 2 is a top view thereof;

FIG. 3 is a left side view of the design of FIG. 1, the right side view being a mirror image thereof;

FIG. 4 is a front view thereof;

FIG. 5 is a rear view thereof; and,

FIG. 6 is a bottom view thereof.

The broken lines form no part of the claimed design, the dash-dot lines are directly adjacent to the claimed areas are included to represent the boundaries of the claimed design and form no part of the claimed design, and any shading is provided to illustrate contour only and is not an indication of texture, gloss, etc.

1 Claim, 3 Drawing Sheets---
